UNITED STATES PATENT OFFICE.

FRANK S. HERETH, OF NEW YORK, N. Y., ASSIGNOR TO E. R. SQUIBB & SONS, A CORPORATION OF NEW YORK.

HERMETIC SEAL FOR RECEPTACLES.

1,100,432.

Specification of Letters Patent. Patented June 16, 1914.

Application filed July 19, 1913. Serial No. 779,899.

To all whom it may concern:

Be it known that I, FRANK S. HERETH, a citizen of the United States, residing at the city of New York, in the borough of Brooklyn and State of New York, have invented certain new and useful Improvements in Hermetic Seals for Receptacles, of which the following is a full, clear, and exact description.

10 The invention relates to bottles and other receptacles, the same being especially designed for use with glass bottles adapted to contain highly volatile substances such as chloroform, ether, and the like.

15 Attempts have been made heretofore to provide hermetic seals for vitreous receptacles by casting, cementing, embedding or otherwise securing a metallic seal-seat to the mouth of the receptacle to form a base to

20 which the seal itself may be secured, but it has been found to be practically impossible to obtain an absolutely impervious joint between the mouth of the bottle and the seal-seat. Where heat is used to secure the seal-

25 seat to the mouth of a vitreous receptacle the differences between the coefficients of expansion of the metal and the vitreous substance is sufficient to cause the fracturing or crushing of the mouth of the receptacle by

30 the shrinking of the metal seat upon cooling. This has necessitated the interpositioning of a yielding medium between the mouth of the receptacle and the seal-seat, but as such a medium is necessarily porous

35 its use is highly objectionable where a perfectly impervious joint is essential.

The object of my invention is to overcome these objections to the use of metallic seal-seats and, in addition, to provide a seal-seat, in combination with a hermetic seal, which may be readily secured to the receptacle adjacent to the mouth thereof and yet be joined thereto in such a manner that an absolutely impervious joint is obtained between the receptacle and the seal-seat.

45 My invention therefore consists of the bottle or receptacle, having a layer of metal electroplated thereto, adjacent its mouth, the said layer of metal forming a base or seal-seat, and a seal secured to said seat for hermetically closing the receptacle.

In the drawing wherein like reference characters refer to like parts, Figure 1 is an

elevation of a receptacle having its mouth hermetically closed with my improved form 55 of seal; Fig. 2 is a vertical section of the same, showing the seal and seal-seat.

The bottle 1, of glass or other vitreous material, is provided with the usual neck 2 having a flange 3 surrounding the mouth of 60 the bottle. A layer or band 4 of nickel, silver or other metal, is applied to the flange 3 by any of the well known processes for electroplating metal on glass or other vitreous substances. This metallic layer or band 65 4 has been shown as extending over the top and sides of the flange 3 and forms a seal-seat or base to which may be secured a seal 5. It is obvious, however, that this band or seal-seat may be located at any suitable 70 point on the bottle, adjacent the mouth thereof. The seal 5 is preferably a metallic disk of soft metal, such as lead or the like, the peripheral edges of which are fused, soldered or otherwise secured to the seal-seat 75 4 to hermetically close the bottle.

It is evident that by electroplating the layer or band 4 to the bottle an intimate contact is obtained between the vitreous substance of which the bottle is made, and the 80 metal, which will be so perfect as to form an absolutely impervious joint between the two. The danger of leakage or loss of a liquid through the impervious joint thus obtained, even when a highly volatile liquid is 85 contained within the receptacle, is thereby entirely eliminated.

When it is desired to use the contents of the bottle, the seal 5 may be punctured or entirely removed from the seal-seat by heating the same, or in any other way, the particular manner in which the seal is opened forming no part of the invention.

Having now described my invention, what I claim, is:—

90 A sealing device for bottles comprising an electro-deposited layer of metal around the lip of the bottle in combination with a metallic disk closing the mouth of the bottle and soldered to said electro-deposited layer. 100

In witness whereof, I subscribe my signature, in the presence of two witnesses.

FRANK S. HERETH.
